(57) **CLAIM**

I claim the ornamental design for a unit assembly for a makeup powder palette, as shown and described.

DESCRIPTION

FIG. 1 is the front view of the housing of the first embodiment for a unit assembly for a makeup powder palette; FIG. 2 is the back view thereof;

FIG. 3 is the left side view thereof;

FIG. 4 is the right side view thereof;

FIG. 5 is the top view thereof;

FIG. 6 is the bottom view thereof;

FIG. 7 is the front view of the powder tray of the unit assembly for a makeup powder palette;

FIG. 8 is the back view thereof;

FIG. 9 is the left side view thereof;

FIG. 10 is the right side view thereof;

FIG. 11 is the top view thereof, the bottom view being a mirror image;

FIG. 12 is the front view of the mirror of the unit assembly for a makeup powder palette;

FIG. 13 is the back view thereof;

FIG. 14 is the left side view thereof;

FIG. 15 is the right side view thereof;

FIG. 16 is the top view thereof, the bottom view being a mirror image;

FIG. 17 is the front view of the unit assembly for a makeup powder palette shown in a closed assembled state;

FIG. 18 is the back view thereof;

FIG. 19 is the left side view thereof;

FIG. 20 is the right side view thereof;

FIG. 21 is the top view thereof;

FIG. 22 is the bottom view thereof;

FIG. 23 is a perspective view thereof shown in a closed assembled state;

FIG. 24 is a perspective view thereof shown in an open assembled state; and

FIG. 25 is a perspective view thereof illustrating the powder tray and mirror partially removed.

FIG. 26 is the front view of the housing of the second embodiment for a unit assembly for a makeup powder palette;

FIG. 27 is the back view thereof;

FIG. 28 is the left side view thereof;

FIG. 29 is the right side view thereof;

FIG. 30 is the top view thereof;

(Continued)

FIG. 31 is the bottom view thereof;
 FIG. 32 is the front view of the powder tray of the unit assembly for a makeup powder palette;
 FIG. 33 is the back view thereof;
 FIG. 34 is the left side view thereof;
 FIG. 35 is the right side view thereof;
 FIG. 36 is the top view thereof, the bottom view being a mirror image;
 FIG. 37 is a perspective view thereof shown in a closed assembled state;
 FIG. 38 is a perspective view thereof shown in an open assembled state; and
 FIG. 39 is a perspective view thereof illustrating the powder tray partially removed.
 FIG. 40 is the front view of the housing of the third embodiment for a unit assembly for a makeup powder palette;
 FIG. 41 is the back view thereof;
 FIG. 42 is the left side view thereof;
 FIG. 43 is the right side view thereof;
 FIG. 44 is the top view thereof;
 FIG. 45 is the bottom view thereof;
 FIG. 46 is the front view of the mirror of the unit assembly for a makeup powder palette;
 FIG. 47 is the back view thereof;
 FIG. 48 is the left side view thereof;
 FIG. 49 is the right side view thereof;
 FIG. 50 is the top view thereof, the bottom view being a mirror image;
 FIG. 51 is a perspective view thereof shown in a closed assembled state;
 FIG. 52 is a perspective view thereof shown in an open assembled state; and,
 FIG. 53 is a perspective view thereof illustrating the mirror partially removed.

The housing, powder tray, and mirror are shown separately for convenience of illustration.
